ELIAS BERSON, OF NEW YORK, N. Y.

METAL STAIRWAY CONSTRUCTION.

Application filed January 13, 1926. Serial No. 81,064.

This invention relates to stairway constructions and refers more particularly to improvements in metal stairways.

At the present time it is the general practice in erecting metal stairways to rivet, bolt, or otherwise connect the riser of one step with the tread of an adjacent step and the tread with the brackets of the stringpieces. It is obvious that under this practice considerable time and labor are involved and hence it is an object of the present invention to overcome the above-recited objectionable features and disadvantages by constructing the elements of a metal stairway in such a manner as to eliminate the necessity of riveting, bolting, or employing other similar means of connecting the elements when erecting or assembling the same.

20 The invention furthermore comprehends a metal stairway which is comparatively simple in its construction and mode of assembly, which is inexpensive both in the production of the elements which make up 25 the stairway and in the operation of assembly, and which is highly efficient, strong and durable.

With the above recited and other objects in view, reference is had to the following specification and accompanying drawings in which there is exhibited one example or embodiment of the invention which is in no way intended as a limitation upon the scope of the appended claims 35 as it is to be clearly understood that variations and modifications which properly fall within the scope of said claims may be resorted to when found expedient.

In the drawings—
40 Figure 1 is a fragmentary vertical sectional view through a stairway constructed in accordance with the invention;

Fig. 2 is a fragmentary detail transverse sectional view taken approximately on the line 2—2 of Fig. 1, and

Fig. 3 is a collective perspective view of certain elements of the stairway.

Referring to the drawings by characters of reference, 10 designates a stringpiece, a 50 pair of which are obviously used in connection with each stairway, and 11 indicates generally the steps, each of which includes a horizontal tread member 12 and a vertical riser member 13, which are preferably formed integral, the tread member being 55 formed at its forward end with an upward-

ly bent terminal 14 and an inwardly bent extremity 15 defining a nose. In order to support each step from and between a pair of stringpieces 10, an angle bracket 16 is 60 secured to the inner sides of the stringpiece 10, preferably by riveting the vertical or base flange 17 to the stringpiece so that the horizontal flange 18 thereof constitutes a shelf upon which the end of the tread 65 member of each step rests.

As heretofore set forth, it is the common practice in erecting or assembling the stairway, when building the same to rivet the treads 12 to the horizontal shelves 18, and 70 under this practice the risers 11 are provided with an angularly horizontally disposed upper end which is riveted to the tread. However, in contradistinction to this the present invention contemplates the elimination of the riveting or bolting of these elements by forming the tread adjacent the nose, with a transversely disposed upwardly offset portion 19 defining on the under side a groove 20 within which the upper edge 80 of the riser of the next adjacent lower step is received. In lieu of rivets, the tread members of the steps are connected to the shelves 18 by means of upstruck tongues 21 in the shelves 18, which tongues are received in openings or slots 22 formed in the opposite ends of the treads. The angle brackets 16, however, are riveted as at 23, at the factory or place of production of the parts, so that the stair builder when the 90 material is received at the place where it is to be erected, has only to properly position the stringpieces 10, set the steps on the brackets, position the grooves 20 over the upper edges of the risers, insert the 95 tongues 21 through the openings or slots 22, and bend the tongues 21 over, as illustrated clearly in Fig. 2. A filler F, such as cement or other material, is then placed on the treads 12 between the stringpieces, 100 the noses and the risers.

It is therefore obvious from the foregoing that a substantial saving or economy both in time and labor, is effected as the elimination of riveting or bolting when 105 erecting and assembling a stairway is obtained and this without sacrificing strength or durability of the structure when completed.

What is claimed is:

1. In a metal stairway construction, steps having transverse grooves in the under side

of the treads adapted to receive the upper edges of the risers, and stringpieces having step brackets provided with bendable upstanding tongues, the tread members having openings through which the tongues are received, with the terminals laterally bent.

2. A metal stairway, including stringpieces, angle brackets secured to the inner faces thereof having horizontal flanges provided with upstanding bendable tongues,

step members including vertical riser portions and horizontal tread portions, the latter having apertures in the opposite ends for the reception of the bendable tongues, ¹⁵ the terminals of which are laterally bent to overlie the same, and upwardly offset transverse grooves adjacent the nose of each step adapted to singly receive the upper edge of the riser of the next adjacent lower ²⁰ step.

ELIAS BERSON.
